Attorney

UNITED STATES PATENT OFFICE

2,587,659

ADJUSTABLE OFFSET LADDER

William C. Smith, Brentwood, Md.

Application December 9, 1949, Serial No. 132,184

2 Claims. (Cl. 228—27)

(Granted under the act of March 3, 1883, as
amended April 30, 1928; 370 O. G. 757)

1

The invention described herein may be manufactured and used by or for the Government of the United States for governmental purposes without payment to me of any royalty thereon in accordance with the provisions of the act of April 30, 1928 (ch. 460, 45 Stat. L. 467).

This invention relates to step ladders having retractile legs and particularly to one which has a secondary leg for supporting one end of one or more steps or rounds between the floor level and the first full width step. In the accompanying drawings which are illustrative of a preferred embodiment of my invention:

Figure 1 is an elevation of my ladder with one adjustable length side rail or leg and one adjustable length brace leg in retracted position.

Figure 2 is a side elevation as seen from the right of Figure 1.

Figure 3 is an enlarged detail of a portion of the retractile leg showing a preferred means for clamping the retractile section in any desired position.

In these drawings:

10 represents a novel offset ladder member which includes a side rail 11, a top step 12, and intermediate steps 13, 14, and 15 of the type commonly used in step ladders. A companion side rail 16 is rigidly secured to the steps 12, 13, 14, and 15 while a retractile rail section 17 is secured to the main side rail 16 by U-shaped collars, or sleeves 18 and suitable wing bolts 19. A secondary side rail 20 is rigidly secured to the underside of the step 15 about midway between the side rails 11 and 16 to provide a support for one end of each of a plurality of steps 21 and 22. There are also provided a brace rail 23 corresponding to the side rail 11 and a companion brace rail 24 corresponding to the side rail 16 upon which latter rail is adjustably mounted a retractile rail section 25, corresponding to the rail section 17. The rail section 25 is also attached to the section 24 by sleeves 18 and wing bolts 19.

The ladder may also be provided with a folding shelf 26 and a folding brace 27 of well known types.

My novel ladder is particularly adapted for use in narrow spaces left after the installation of counters, window air-conditioned units, desks, tables, or the like. Either or both of the adjustable side rail or adjustable brace may be supported upon the obstructing unit or article of furniture while the half width steps 21 and 22 provide a means for mounting the ladder without resort to the use of boxes or the like for climbing up to or down from the step 15. These ladders may be made in rights and lefts to provide the maximum utility of my invention. However, when the invention is applied to straight or extension ladders merely turning the ladder 180 degrees serves to convert it from a right to a left

2

and vice versa. By enabling the user of my ladder to move closer to his work than with the usual form of ladder the hazard of falling is materially reduced. Two or more may be used with planks to form a scaffold on sloping ground for painting or glazing a house.

It should be understood that the present disclosure is for the purpose of illustration only, and that the invention includes all modifications and equivalents which fall within the spirit and scope of the appended claims, in which it is my intention to claim all novelty inherent in my invention as broadly as possible in view of the prior art.

15 What is claimed is:

1. A step ladder of the class described including a front retractile leg, a companion front non-retractile leg, a secondary leg intermediate of said front outer legs, a plurality of steps connecting said secondary leg and said non-retractile leg below the highest position of said retractile leg and a rear bracing member comprising a retractile leg in alignment with said front retractile leg and a companion non-retractile leg.

2. A ladder including an outer front retractile leg, a companion outer non-retractile front leg, a secondary front leg intermediate of said outer front legs, a plurality of steps connecting said outer front legs, a second plurality of steps connecting said non-retractile front leg and said secondary front leg below the uppermost position of said front retractile leg, a rear bracing member comprising a retractile leg in alignment with said outer front retractile leg and a companion non-retractile bracing leg in alignment with said outer front non-retractile leg, whereby said ladder may be used in passages less than the width of the ladder with said two retractile legs supported on an offset such as a windowsill, a radiator or an article of office furniture, while said non-retractile legs are supported on the floor adjacent to said offset support.

WILLIAM C. SMITH.
